Primary Examiner — Mojtaba Tehrani

(57) **CLAIM**

The ornamental design for an ice maker, as shown and described.

DESCRIPTION

FIG. 1 is a front view of an ice maker showing my new design;

FIG. 2 is a rear view thereof;

FIG. 3 is a left side view thereof;

FIG. 4 is a right side view thereof;

FIG. 5 is a plan view thereof;

FIG. 6 is a bottom view thereof;

FIG. 7 is a perspective view thereof;

FIG. 8 is an enlarged, detailed view of the rear view, as shown in FIG. 2; and,

FIG. 9 is an enlarged, detailed view of the rear view, as shown in FIG. 2.

The evenly broken lines in the drawings depict the unclaimed portions of the ice maker; the dash-dot broken lines disclose unclaimed boundaries of the isolated/enlarged views; the broken lines form no part of the claimed design.

1 Claim, 9 Drawing Sheets(56)
